UNITED STATES PATENT OFFICE.

JOHN L. SOMMER, OF NEWARK, NEW JERSEY.

DESIGN FOR A BUTTON-HOOK.

SPECIFICATION forming part of Design No. 25,602, dated June 9, 1896.

Application filed February 15, 1896. Serial No. 579,459. Term of patent 14 years.

To all whom it may concern:

Be it known that I, JOHN L. SOMMER, a citizen of the United States, residing at Newark, in the county of Essex and State of New Jersey, have invented a new and original Design for the Handles of Button-Hooks and Similar Articles, fully described and represented in the following specification and the accompanying drawings, forming a part of the same.

This invention relates to a novel shape for the handles of that class of button-hooks and similar articles which are formed of a continuous wire suitably bent at one end to produce the handle; and the invention consists in the specific shape for such handle, herein shown and described.

In the annexed drawings, Figure 1 is a perspective view of a button-hook embodying my present design; and Figs. 2 and 3 are transverse sectional plan views of the same on lines *x x* and *y y*, respectively, in Fig. 1.

The shank *a* is shown formed at one end with the hook *b* of the usual form and bent at the opposite end into a handle *c*, continuous therewith and formed with convexly-curved ends joined by an intermediate portion of concave curvature. The shank of the article is made of round cross-section and is

slightly flattened where it joins the handle, which is formed with flat sides and rounded edges, as shown. The end of the handle adjacent to the shank is of smaller curvature than that of the opposite end, and the junction of the shank with the side of the handle with which it is continuous is by a gradual curve. The extremity of that portion of the wire composing the article which forms the handle is abutted against the curved junction of the shank at right angles thereto.

The characteristic features of the design are the specific details of form of the handle and its relation to the shank described above and illustrated in the drawing.

Having thus set forth the invention, what I claim herein, and desire to secure by Letters Patent of the United States, is—

The design for the handles of button-hooks and similar articles substantially as herein shown and described.

In testimony whereof I have hereunto set my hand in the presence of two subscribing witnesses.

JOHN L. SOMMER.

Witnesses:

MAXIMILIAN G. HANGS,
HENRY J. MILLER.
